UNITED STATES PATENT OFFICE.

ALFRED V. P. MARTIN, OF BROOKLYN, NEW YORK.

HAIR-CURLER.

1,354,117.

Specification of Letters Patent. Patented Sept. 28, 1920.

Application filed November 11, 1919. Serial No. 337,313.

To all whom it may concern:

Be it known that I, ALFRED V. P. MARTIN, a citizen of the United States, and a resident of the city of New York, borough 5 of Brooklyn, in the county of Kings and State of New York, have invented a new and Improved Hair-Curler, of which the following is a full, clear, and exact description.

10 The object of the invention is to provide a new and improved hair curler arranged to enable the user to readily curl a strand of hair around one member of the curler and then to securely fasten the curled 15 strand in position. Another object is to enable the user to readily close and open the hair curler without danger of its parts becoming entangled in the hair. Another object is to provide a hair curler which is 20 simple and durable in construction, cheap to manufacture and easily manipulated by the user.

With these and other objects in view, the invention consists of certain novel features 25 of construction as hereinafter shown and described and then specifically pointed out in the claims.

A practical embodiment of the invention is represented in the accompanying drawings forming a part of this specification, 30 in which similar characters of reference indicate corresponding parts in all the views.

Figure 1 is a perspective view of the improved hair curler with the parts in closed 35 position;

Fig. 2 is an enlarged plan view of the same;

Fig. 3 is a side elevation of the same with a curled strand of hair clamped in position 40 on the hair curler, part of the latter being shown in section;

Fig. 4 is a perspective view of a modified form of the hair curler with the parts in open position;

45 Fig. 5 is a sectional side elevation of the same with the parts in closed position; and

Fig. 6 is a perspective view of another modified form of the hair curler with the parts in open position.

50 The improved hair curler illustrated in Figs. 1, 2 and 3, comprises in its general construction a curling member 10 and a clamping member 11. The curling member 10 is in the form of a comparatively stiff 55 open frame, preferably made of wire, and having side arms 12 and 13 connected with

each other at the forward end by a cross-bar 14 and provided at the rear end with angular terminals 15 extending toward each other. The clamping member 11 is 60 preferably made of resilient sheet material and is somewhat less in width than the distance between the side arms 12 and 13 of the curling member 10 to permit of passing the free end of the clamping member 11 65 under the crossbar 14, with a view to interlock the curling and clamping members, as hereinafter more fully explained. The rear end of the clamping member 11 is provided with a return bent portion forming 70 a crosshead 16 mounted to slide lengthwise on the side arms 12 and 13. The rear portion 17 of the crosshead 16 is in the form of a chamber for the passage of the angular terminals 15, which latter are adapted 75 to abut against the rear ends of the crosshead 16 thus limiting the sliding movement of the crosshead 16 on the side arms 12 and 13 of the curling member 10, as will be readily understood by reference to 80 the full and dotted line positions shown in Fig. 2. It will be noticed that when the crosshead 16 is in rearmost position on the side arms 12 and 13 then the free end of the clamping member 11 is spaced from the crossbar 14, and the clamping member 11 owing to its resiliency swings upward 85 into open position with the return bent portion acting as a fulcrum.

When the clamping member 11 is in this 90 open position, indicated in dotted lines in Fig. 3, then a strand of hair 20 can be readily curled around the curling member 10, as shown in Fig. 3, and when this has 95 been done a forward sliding movement is given to the clamping member 11 and at the same time the forward free end thereof is bent downward so as to cause the free end to pass under the crossbar 14 thus locking the clamping member in position on the curling member, at the same time exerting a pressure against the curled strand of hair, thus securely holding the latter 105 clamped between the curling member 10 and the clamping member 11. When it is 110 desired to release the curled strand of hair 20, it is only necessary for the user to slide the clamping member 11 rearwardly to disengage the free end of the clamping member from the crossbar 14 to allow the clamping member to swing by its own resiliency into open position, thus releasing the curled

strand of hair. The curling member 10 can now be readily withdrawn or pulled out from the curled strand of hair and without the slightest danger of the hair becoming 5 entangled in the parts of the hair curler.

In the modified form shown in Figs. 4 and 5, the curling member 30 is made in the form of a stiff wire frame having side arms 31, 32, a front crossbar 33 and angular terminals 34 10 at the rear ends of the side arms 31 and 32. The clamping member 35 is made, in this case, of a piece of wire doubled upon itself and terminating in transversely extending trunnions 36 engaging bearings 37 formed 15 in the rear chamber portion 38 of a crossbar 39 mounted to slide lengthwise on the side arms 31 and 32 but having a limited sliding movement thereon owing to the angular terminals 34 extending in the chamber 38. The 20 hair curler is used in the same manner as above described in reference to the one shown in Figs. 1, 2 and 3, so that further description of the same is not deemed necessary, it being, however, understood that 25 when the crosshead 39 is in rearmost position, the clamping member 35 has its free end disengaged from the crossbar 33, and after the strand of hair is curled on the curling member 30 then the clamping member 30 35 is swung downward into engagement with the hair and slid forward, with the free end of the clamping member passing under the crossbar 33 to lock the members together.

35 In the modified form shown in Fig. 6, the curling member 40 is in the form of a wire frame having side bars 41, 42 and a front crossbar 43 and angular rear terminals 44 fitting into the ends of a tube 45. The 40 clamping member 50 of this hair curler is made of a single piece of wire doubled up to form the clamping member, the doubled-up piece having its ends provided with return bends 51, 52 terminating in coils 53, 54 45 slidingly engaging the side bars 41, 42. The forward sliding movement of the clamping member 50 is limited by the return bends 51 and 52 abutting against the tube 45. The hair curler shown in Fig. 6 is used in the

same manner as above described relative to the hair curler shown in Figs. 1, 2 and 3, so that further description of the same is not deemed necessary, it being understood that the clamping member 50 is mounted to swing on the return bends 51 and 52 as the fulcrum while the coils 53 and 54 form a crosshead slidingly engaging the side arms 41 and 42 of the curling member 40.

Having thus described my invention, I claim as new and desire to secure by Letters Patent:—

1. As an article of manufacture, a hair curler comprising a curling member around which a strand of hair is adapted to be curled, and a clamping member adapted to clamp the curled strand of hair in position on the said curling member, the said curling and clamping members being slidingly connected with each other at one end to allow of moving the said curling and clamping members lengthwise one on the other, the said clamping member being arranged to swing up and down with the sliding end as the fulcrum to allow of opening and closing the clamping member relative to the curling member, the free end of the clamping member being adapted to pass into interlocking engagement with the free end of the said curling member on moving the clamping member forward on the curling member and while holding the clamping member depressed.

2. As an article of manufacture, a hair curler comprising a curling member in the form of an open and comparatively stiff frame, and a clamping member of resilient material provided at one end with a return bent portion terminating in a crosshead having a limited sliding movement on the corresponding end of the curling member, the said clamping member being mounted to swing on its return bent portion as the fulcrum, and the free end of the said clamping member being adapted to pass under the free end of the said curling member to lock the clamping member against swinging movement when in closed position.

ALFRED V. P. MARTIN.
